United States Patent Office

Des. 213,600
Patented Mar. 18, 1969

213,600

PORTABLE BROILER

Edwin J. Cowan, 275 Manzanita,
Sierra Madre, Calif. 91024

Filed May 16, 1968, Ser. No. 11,964

Term of patent 14 years

U.S. Cl. D81—10
Int. Cl. D7—04

FIG. 1.

FIG. 3.

FIG. 2.

FIG. 1 is a perspective view showing the front, top and left end of the portable broiler;

FIG. 2 is a perspective view showing the rear, bottom and right end of the portable broiler; and

FIG. 3 is a left end view of the portable broiler.

The fuel tank shown in broken lines in FIGURES 1 and 2 is included for illustrative purposes only.

I claim:

The ornamental design for a portable broiler, substantially as shown and described.
